UNITED STATES PATENT OFFICE.

CHARLES PONTEZ, OF OMAHA, NEBRASKA.

IMPROVEMENT IN EARTH-BORING AND TUBE-SINKING APPARATUS.

Specification forming part of Letters Patent No. 146,202, dated January 6, 1874; application filed February 21, 1873.

To all whom it may concern:

Be it known that I, CHARLES PONTEZ, of Omaha, in the county of Douglas and State of Nebraska, have invented a new and Improved Apparatus for Raising Earthy Matters and Sinking Tubes, of which the following is a specification:

The invention relates to improvements in pneumatic earth elevating and discharging apparatus, for use in sinking wells, shafts, &c.; and consists in a certain construction and arrangement of parts, as hereinafter described, and explicitly set forth in the claims.

Figure 1 is a sectional elevation of a foundation-tube, a coffer, and an air-box for the drills, and a side elevation of the pneumatic ejecting apparatus. Fig. 2 is a sectional elevation of a foundation-tube and an air-lock, and a side elevation of the drilling and ejecting apparatus. Fig. 3 is a section on the line $\alpha\alpha$ of Fig. 1. Fig. 4 is an inverted plan of the bottom of a drill and air box. Fig. 5 is an inverted plan of the bottom, showing a modified form of drill. Fig. 6 is a plan of an air-box for a drill adapted for the removal of bodies too large to be ejected by the pneumatic apparatus, the coffer represented in Fig. 1 being used in connection with it; and Figs. 7 and 8 represent different forms of augers that may be used instead of the drills.

A is the pipe through which the air for ejecting the earthy matters is to be forced down to the earth to be raised. B is the ejecting-tube, and to the lower ends of these two tubes, A and B, I attach an air-box, C, which is open at the under side to the earth, and in this I arrange drills D for being turned by the shaft, which will be revolved by power suitably applied at the top, to loosen up the earth, also scrapers E for scraping it up to the opening into the ejecting-tube. The drills, which consist of conical points projecting from arms, will be arranged at an inclination of about thirty degrees, as shown in Fig. 1, to cause the loosened earth to rise on a cone to the center, which it is believed will give the best results in working the earth into the ejecting-tube. The form and arrangement of these drills may vary, however, as may be found best, as indicated by Fig. 4. The air, being forced into the drill-box, escapes, of course,

through the ejecting-tube, and carries up the earth when it is sandy or of other fine homogeneous nature, letting the foundation-tube F settle down regularly and truly. In this case the drill-box is rounded, as shown in Fig. 5; but for working in earth containing stones, or other bodies too large to be ejected by the pneumatic apparatus, I construct it, as represented in Fig. 6, with recesses G, so that it will at each revolution uncover some of the surface over which it works; and I use the coffer H, which, being kept charged in the lower part with air by the tube I, will have a workman in it to remove the stones or other objects through the recesses G, and will be raised up from time to time to be discharged. The raising of said coffer will be effected by discharging the water with which the upper chamber K will be filled to sink the coffer, the discharge being effected by allowing the air to be forced in through the pipe L, and the water out through the pipe M. With this contrivance I can remove obstructions which would effectually prevent the use of the pneumatic apparatus alone, or with the drill. This coffer has a tube, N, at the center, which works on the shaft-tubes A and B as a guide, by which to keep it clear of the flanges by which the sections of the foundation-tubes are joined.

In practice, I propose to use an air-lock with this drilling and ejecting apparatus, to afford access to it for removing objects too large for escaping by the ejecting-tube. N', Fig. 2, represents the plates or disks of the air-lock, fixed in the tube F to be sunk, through which the shaft B passes, and to pack the holes for it air-tight. I have an india-rubber washer, O, surrounding the shaft B, and attached to the top of the drill-box, to meet a corresponding disk, P, in the bottom plate of the air-lock, when the drill-box is raised up to it to allow the workman to descend below the drill-box, which makes an air-tight joint at the hole for the shaft. The upper disk is also provided with a rubber packing-washer, Q, against which a washer, R, on the shaft comes to pack the hole in the disk; and to prevent the escape of air through the shaft B, its upper end is closed with a ball, T. The cylinder is then cleared of water, and the workman descends through the doors V in the disks N', which open down-

ward. The drill-box does not obstruct the opening of the lower door, in consequence of the recesses G, one of which is adjusted under the door to allow it to open and the workman to descend. When the drill is in operation with this air-lock, and let down below it, so that the washers will not pack against the disks, the upper washers will be held down with clamps W.

Instead of the drills above described, I may use closed conical augers, either inverted or with the base downward, as represented in Figs. 7 and 8. These augers are adapted to sandy or gravelly soils, and to work at great depth, as they prevent the air or water used for ejecting the earth from being absorbed by the soil under the constantly increasing pressure. Water may, of course, be used in the ejecting apparatus instead of air. By the air-box in connection with the drills, large tubes can be cheaply sunk in sandy soils without the expense of the air-locks, also small ones, in which the air-lock could not be used.

Having thus described my invention, I claim as new and desire to secure by Letters Patent—

1. The combination of the air-box with the drills or augers and ejecting-tubes, substantially as specified.

2. The combination of the coffer with the drills, air-box, and ejecting-tubes, substantially as specified.

3. The air-box, provided with one or more recesses, G, to afford access from above to the earth below, substantially as specified.

4. The oblique arrangement of the drills and scrapers relatively to the ejecting-tube, to facilitate the delivering of the earth thereto, substantially as specified.

5. The arrangement of the coffer with the tube-shaft B, to be guided by it, substantially as specified.

CHARLES PONTEZ.
